UNITED STATES PATENT OFFICE

MARTIN EULE, OF BERLIN-SPANDAU, GERMANY, ASSIGNOR TO SIEMENS-SCHUCKERT-WERKE AKTIENGESELLSCHAFT, OF BERLIN-SIEMENSSTADT, GERMANY, A CORPORATION OF GERMANY

HIGH PRESSURE TUBULAR BOILER

Application filed November 14, 1927, Serial No. 233,164, and in Germany November 18, 1926.

My invention relates to a high pressure tubular boiler and more particularly to such a boiler designed as a vertical shaft boiler with heater tubes arranged in the radiation chamber and superheater tubes located in flues of the boiler.

The object of my invention is to simplify the guidance or conduct of the gases and the construction of the entire steam generator. 10 This task is solved by the gases of combustion flowing with a single reversal at the end of the radiation chamber in one stream through the superheater portion of the pipe system and through the air heater arranged above 15 the superheater portion.

The drawings affixed hereto and forming part of my specification show the total structure of the steam generator and a number of details which are particularly suitable for 20 the construction of the steam generator of the design specified.

These drawings represent in:

Fig. 1, a longitudinal vertical section through the complete steam generator embodying my invention, 25

Figs. 2 and 3 horizontal sections through the generator on the lines 2—2 and 3—3, respectively of Figure 1,

Fig. 4, an enlarged horizontal section 30 through a portion of the air collecting and distributing boxes, on the line 2—2 Figure 1.

Fig. 5, an enlarged vertical section through a part of the roof portion of the combustion and steam generating chamber shown in 35 Fig. 1,

Figs. 6^{a-b} and 7^{a-b} differently shaped sectional portions of the steam generating tubes in front (a) and side (b) elevation respectively, 40

Fig. 8 a front elevation of the upper part of the sectional portions of Figs. 6^a and 7^a nested into each other,

Fig. 9 a section of the radiating chamber dome on the line 9—9 in Fig. 5, and in 45

Fig. 10 an enlarged view of the steam distributor 44, Fig. 1.

Referring to Figs. 1 to 3 of the drawings, in which the straight course of the gases is particularly clearly shown, which follows from 50 the design of the steam generator, 1 is the

radiation chamber in which the combustion occurs and from which the gases pass in a single turn around the lower edge into the superheater portion 2 arranged in an annular flue in series with the radiation chamber, 55 traverse the air heater 3 and pass through the flues 4 into the stack 5. The necessary draft is produced by the fan or propeller 6.

The steam generator is constructed as follows. Double T-girders 7, Figs. 2 and 3, extend from the foundation upwards and support the roof structure. From this roof structure are suspended substantially all the parts constituting the steam generator. 60

These parts are thus supported from the top and not from the bottom, as usual, which is one of the main characteristics of my improved steam generator. The steam generating tubes 47 form the vertical wall of the radiation chamber 1 which chamber is supplied with heat from the top, as will be described later. The flue located externally to 65

the radiation chamber forms an annular chamber around it and is subdivided into separate sections or compartments A, B, C 70 and so on in which are located alternately superheater coil systems 8 and intermediate superheater coil systems 9. The superheaters consist of individual coils suspended 75

from two carrier rings 10. The inner carrier ring is supported by tubular suspension elements 11 from the roof structure and the outer ring is supported by the upright girders 7. Since it is practically impossible to entirely protect the suspension tubes from 80

exposure to the heat, cooling air is forced through them. This feature is not illustrated as it is an obvious expedient. 85

The flue gas compartments containing the superheaters open at the top into the air heaters 3 from the top of which extend flue conduits 4. The flues 4 converge into a dome and open into a stack 5 by way of a dust separator to be described later. 90

As Fig. 1 of the drawings shows the steam generator does not contain any brickwork in its interior. In order to avoid radiation and conduction losses the segments or compartments which contain the superheating pipes are enclosed towards the outside by walls con- 95

sisting of heat insulated iron panels 12 built up of individual sections which are so arranged that they may be removed as a whole or at least in large-sized slabs or panels. In order to be able to utilize the remaining heat which is conducted through the brickwork and also the amount of heat which tends to be conveyed through the outside walls of the superheater and the air heater, the individual section walls are provided on the outside with air jackets 13 which are traversed by the cold air of combustion (see dash-dot line Figure 1) before it reaches the air heaters 3. The individual sections of the furnace shaft are thus insulated from the external air by a jacket of air.

From the air heaters 3 the highly heated air is conducted (as shown by the dash-dot arrow line) into the air collecting boxes 14 (see also Figure 4) from which it is conducted as primary air into the pulverized coal burners 15 and as secondary air directly into the combustion chamber, as will be described in detail later.

The ashes are collected in an ash hopper 16 after they have been cooled down by the loops 17 and 18 formed by the heater tubes 47. Experience has proven that not all the ashes are precipitated, but that a portion is carried along by the combustion gases in the form of flue ashes. In order to separate these ashes from the flue gases after they have reached the foot of the stack, the ash laden gases are forced to alter their direction of travel and to reduce their velocity. For this purpose a cone shaped baffle element 19 is provided with lateral openings 20 through which the deflected gases pass in the direction of the arrow lines from the stack into a large chamber 21. Owing to the great reduction in velocity and sharp diversion the flue ashes are precipitated, collect in the hoppers 23 and may be removed from there by flushing with water. The flue gases re-enter the stack through openings 22 and are discharged by it into the atmosphere. The reversal of the direction of the flow of the gases is further assisted by a portion of the hot flue gases being deflected through conduits 24 towards the coal preparation plant for drying purposes (not shown here). The draft of these conduits is in the direction of the inverted U arrow line and thus opposite to the draft in the chimney whereby the intended reversal of the flow and reduction of the velocity is effectively assisted.

The design of the combustion air collecting boxes or chests 14 is particularly clearly shown in Fig. 4 of the drawings. To the stay plates 25, extending inwardly from the inner walls of air heaters 3, vertical angle irons 26 are attached. Over these angle irons are slipped cast-iron plates 27 which are held on the angle-irons by claw-like extensions 28. The cast-iron plates 27 are in-

serted from the top and are maintained in position by gravity. The stay plates 25 are perforated so that a substantially continuous annular chamber 14 is formed around the radiation chamber, which contains the highly heated air of combustion. The supply of the secondary air to the combustion chamber is effected by nozzles 29 pivoted in openings provided in the cast-iron plates 27, and through which the air can pass from the annular chamber into the combustion chamber. The mechanism for adjusting the nozzles 29 is clearly shown in Fig. 5 of the drawings. The nozzles 29 are linked to a common shaft 30 which can be moved by means of a link system 30 in the direction of the double arrow in Figure 4. By the aid of these rocking nozzles it is possible to point the entering air jets in the proper direction to produce different whirls of the combustible mixture with- in the combustion chamber.

The nozzles may be located in the walls of the air collecting boxes in such a manner that the combustion process in the furnace may be observed through them. For this purpose an inspection opening 29a is provided in the rear or outer wall of the collecting boxes the axis of which coincides with the axis of the nozzle when the latter is in a certain position as indicated by the dash-dot line in Fig. 4.

The design of the steam generating elements proper is shown in greater detail in the Figs. 6 to 8 of the drawings. The generating tubes 47 are arranged in the radiation chamber in such a manner that they envelop the chamber closely spaced from one, another and so to virtually form the chamber wall, as shown particularly clearly in Fig. 4. The radiation chamber is closely surrounded by a shell of cast-iron plates 27 which form the inner walls of the air collecting boxes 14 and to which the heater tubes are attached by straps or other suitable conventional means not shown here.

The difficulties which would arise in short-bending the heater tubes so that they are located closely together are according to my invention eliminated in the following manner. The total number of generator tubes disposed around the inner circumference of the radiation chamber 1 is circumferentially divided into a suitable number of sections, for convenience of installation, repair and other reasons. The upper portion of such a section, seen from the center of the chamber is shown in Figure 8. Each of these sections is composed of two distinctly separate units 47^a and 47^b (see Figs. 7^a and 6^a respectively) nested into each other and coupled together as will be described presently. The tube, comprising a unit is bent at the upper and lower end of the unit into a number of loops projecting from the chamber wall into the chamber 1 as will be seen for instance from Figures 1

and 6^b. The upper loops are of different size (b and c) to adapt themselves to the radiation chamber dome for the purpose of protecting the dome itself from the heat of radiation, as will be seen from the detail illustration Figure 5. The lower loops 17, 18 similarly projecting into the chamber space (see Figure 1) serve for abstracting the heat from the ashes descending in the chamber, as mentioned hereinbefore. These loops b, c and 17, 18 are not bent individually in one plane, but are offset out of the general plane in which they are bent so that the next vertical straight tube length continuing from the loop is located in another radial plane (with respect to the chamber), so that adjacent vertical tube lengths 47^b are spaced apart a sufficient distance (see Figure 6^a) to permit the accommodation of another vertical tube length in this interstitial space. The other section unit shown in Figures 7^a, 7^b is similarly bent, having the small loops a at the ends and having the vertical straight tube lengths 47^a spaced similarly as described with reference to Figure 6^a. Two of such units Figures 6^a and 7^a are nested into each other, with the vertical lengths 47^a placed into the spaces between vertical lengths 47^b, so that the radiation chamber is entirely encompassed by a substantially closed row of vertical tubes, when all sections are installed. Figure 8 shows the two units nested into each other, with the ends of the tube units protruding upwardly so that they can be conveniently connected into the generating system. In this manner the units can be very easily manufactured in quantity and easily installed or replaced in case of defects.

Fig. 5 of the drawings which shows the operating gear for the rocking nozzles also illustrates the suspension of the generator tubes and the construction of the top arch. On the suspension rods 32 hangs a carrier ring 33 from which the generator tubes are suspended, the ring resting with its outer periphery upon brackets 34 fastened to the uprights 7 carrying the roof (not shown in Figure 5). From the bracket 34 are suspended by rods 35 supports 36 which engage the upper bends of the tube sections either at the outer side of the bend such as tube loops a or at the inner side of the bend, such as tube loops b, so that the tube sections are firmly suspended. To these supports 36 are further more attached by an intermediate link the supporting bails 37 which carry the refractory bricks 38 of which the main arch portion of the shaft is built. These bails 37 are provided with projections 39 adapted to engage correspondingly shaped grooves in the bricks 38. Below the supporting bails 39 are located the tube bends c. Fig. 9 shows this construction in a transverse section on line 9-9 in Figure 5 in a larger scale. It will be observed in this figure that each bail

37 is enclosed by the bricks of the arch from three sides while it is screened from the radiation chamber by a tube loop c traversed by the liquid operating medium. The bails 37 are thus effectively protected from the action of the furnace heat.

Fig. 5 of the drawings also shows the construction of the central arch portion at the top of the radiation chamber. This arch is formed by a mushroom-like individual element 40 which is suspended by rods 41. This arch 40 contains the burners 15. It may be raised by screws 45 so that defective bricks may easily be replaced and the burners repaired.

Above the arch 40 is located a distributing device 44 for steam and water, see Figs. 1 and 10, which operates in the following manner. As shown in larger scale in Figure 10, the distributor consists of six superimposed separate chambers I-VI to each of which the desired tube sections or units of the sections, of which the generating and superheating system is composed are connected for instance as follows. The water delivered into the boiler by the pump (not shown) enters the chamber I through supply pipe 42 whence it is distributed over the individual steam generating tube sections disposed around the wall of the radiating chamber. For instance in this case the water would enter by way of the pipe section forming loops c and b (Figs. 5, 6^a, 6^b) so that thus the dome brick work 38 and its supports 37 are effectively cooled. The steam generated is collected in the next compartment II whence it passes to compartment III by way of throttle D through which its pressure is reduced to that required by the prime mover. From compartment III the steam passes to the superheating coil systems 8 (Figure 3) whence it returns into compartment IV from which it is supplied at M to the prime mover. In case intermediate superheating between the prime mover stages is required the steam returns by way of Z to compartment V of the distributor, whence it is distributed over the intermediate superheating coil systems 9 (Figure 3) provided for that purpose. The re-superheated steam is collected in compartment VI whence it is returned over A to the remaining prime mover stages. The substantial advantage of this arrangement resides in the fact that a uniform distribution of the working medium over all the portions of the system of pipes is ensured, a feature which is of particular importance when the steam is generated under forced circulation and at critical pressure and temperature.

In Fig. 1 of the drawings is also illustrated a circular runway 48 for a crane car by means of which all parts of the shaft may be reached, so that defective parts may easily be repaired or exchanged.

Various modifications and changes may be made without departing from the spirit and the scope of the invention, and I desire, therefore, that only such limitations shall 5 be placed thereon as are imposed by the prior art.

I claim as my invention:—

1. A tubular steam generator for generating steam at high pressure and temperature, 10 having a combustion chamber of symmetrical cross-sectional contour with respect to its axis and having its walls composed of a closely spaced row of steam generating tubes, and a plurality of substantially radial walls forming 15 combustion gas chambers spaced around said combustion chamber and containing further heat absorbing tubes, so that said chambers directly receive the combustion gases from said combustion chamber, the total of 20 the liquid being converted into vapor in the tubes which form the combustion chamber, the heat absorbing tubes in alternate gas chambers acting as steam superheaters and steam re-superheaters.

25 2. A tubular steam generator for generating steam at high pressure and temperature, having a combustion chamber of symmetrical cross-sectional contour with respect to its axis and having its walls composed of a closely spaced row of steam generating tubes, and a plurality of combustion gas chambers 30 spaced around said combustion chamber and containing further heat absorbing tubes, and being constructed to directly receive the combustion gases from said combustion chamber, and collectors and distributors for the operating medium located outside but in the central axis and both at one end of said combustion chamber, the inlets and outlets of said generating tubes and heat absorbing tubes being 35 connected to said collectors and distributors.

3. A tubular steam generator for generating steam of high pressure and high superheat having a combustion chamber of symmetrical cross-section, a plurality of individual combustion gas chambers disposed about the combustion chamber, heating tubes disposed in said chambers and a plurality of air preheaters disposed in line with said gas 45 chambers, the combustion gases passing from the combustion chamber directly into the gas chambers, whereby the direction of gas, flowing from the combustion chamber to the gas chambers is diverted 180° and the gas flow 50 from the gas chamber through said air preheaters occurs in a straight line, and hot air collecting and distributing boxes disposed between said air preheaters and said combustion chamber and intercommunicating with each other and being adapted to receive heated air from said preheaters and having means for distributing it over said combustion chamber, said boxes having removable panel walls facing said combustion chamber.

4. A tubular steam generator for generating steam of high pressure and high superheat having a combustion chamber of symmetrical cross-section, a plurality of substantially radial walls forming individual combustion gas chambers disposed about the combustion chamber, heating tubes disposed in said chambers and a plurality of air preheaters disposed in line with said gas chambers, the combustion gases passing from the combustion chamber directly into the gas chambers, whereby the direction of gas, flowing from the combustion chamber to the gas chambers is diverted 180° and the gas flow 110 from the gas chamber through said air preheaters occurs in a straight line, and hot air collecting and distributing boxes disposed between said air preheaters and said combustion chamber and intercommunicating with each other and being adapted to receive heated air from said preheaters and having means for distributing it over said combustion chamber, said boxes having re- 115

ing steam of high pressure and high temperature having a combustion chamber of symmetrical cross-section and having the walls of the chamber composed of steam generating tubes, a plurality of substantially radial walls forming individual combustion gas chambers disposed about said combustion chamber and heating tubes arranged in said chambers, and a plurality of air preheaters disposed in line with said gas chambers so that the combustion gases pass from the combustion chamber through the gas chambers and air preheaters, and a roof structure above said generator, a roof supporting structure surrounding said generator, and means for suspending said generator tubes, said heating tubes and said air heaters from said roof supporting structure.

5. A tubular steam generator for generating steam of high pressure and high superheat having a combustion chamber of symmetrical cross-section, a plurality of substantially radial walls forming individual combustion gas chambers disposed about the combustion chamber, heating tubes disposed in said chambers and a plurality of air preheaters disposed in line with said gas chambers, the combustion gases passing from the combustion chamber directly into the gas chambers, whereby the direction of gas, flowing from the combustion chamber to the gas chambers is diverted 180° and the gas flow from the gas chamber through said air preheaters occurs in a straight line, and hot air collecting and distributing boxes disposed between said air preheaters and said combustion chamber and intercommunicating with each other and being adapted to receive heated air from said preheaters and having means for distributing it over said combustion chamber, said boxes having removable panel walls facing said combustion chamber.

6. A tubular steam generator for generating steam of high pressure and high superheat having a combustion chamber of symmetrical cross-section, a plurality of substantially radial walls forming individual combustion gas chambers disposed about the combustion chamber, heating tubes disposed in said chambers and a plurality of air preheaters disposed in line with said gas chambers, the combustion gases passing from the combustion chamber directly into the gas chambers, whereby the direction of gas, flowing from the combustion chamber to the gas chambers is diverted 180° and the gas flow from the gas chamber through said air preheaters occurs in a straight line, and hot air collecting and distributing boxes disposed between said air preheaters and said combustion chamber and intercommunicating with each other and being adapted to receive heated air from said preheaters and having means for distributing it over said combustion chamber, said boxes having re- 120

movable panel walls facing said combustion chamber, and air distributing nozzles in said panel walls.

7. A tubular steam generator for generating steam of high pressure and high superheat having a combustion chamber of symmetrical cross-section, a plurality of substantially radial walls forming individual combustion gas chambers disposed about the combustion chamber, heating tubes disposed in said chambers and a plurality of air pre-heaters disposed in line with said gas chambers, the combustion gases passing from the combustion chamber directly into the gas chambers, whereby the direction of gas, flowing from the combustion chamber to the gas chambers is diverted 180° and the gas flow from the gas chamber through said air preheaters occurs in a straight line, and hot air collecting and distributing boxes disposed between said air preheaters and said combustion chamber and intercommunicating with each other and being adapted to receive heated air from said preheaters and having means for distributing it over said combustion chamber, said boxes having removable panel walls facing said combustion chamber, and air distributing nozzles in said panel walls, and means for moving said nozzles, whereby the air jets delivered into combustion chamber can be given the desired direction.

8. A tubular steam generator for generating steam at high pressure and temperature, having a combustion chamber of symmetrical contour with respect to its axis and having its walls composed of a closely spaced row of steam generating tubes, and a plurality of substantially radial walls forming combustion gas chambers spaced around said combustion chamber and containing further heat absorbing tubes, so that said chambers directly receive the combustion gases from said combustion chamber, the total of the liquid being converted into vapor in the tubes which form the combustion chamber, the heat absorbing tubes in alternate gas chambers acting as steam superheaters and steam re-superheaters, said vapor generating tubes being divided into a plurality of groups connected in parallel with each other.

9. A steam generator having a plurality of steam generating tubes enclosing a space to form a combustion chamber, and means for supplying fuel to said chamber, said tubes being arranged in a plurality of groups, each group consisting of two units and each unit comprising a number of straight parallel tube lengths spaced apart approximately the thickness of a tube, said lengths being connected by loops formed at their ends, one unit being nested into the spaces between the tube lengths of the other unit.

10. A steam generator having a plurality of steam generating tubes enclosing a space

to form a combustion chamber, and means for supplying fuel to said chamber, said tubes being arranged in a plurality of groups, each group consisting of two units and each unit comprising a number of straight parallel tube lengths spaced apart approximately the thickness of a tube, said lengths being connected by loops formed at their ends, the loops extending radially into said chamber, one unit being nested into the spaces between the tube lengths of the other unit, and one unit having larger loops extending into said chamber further than those of the other unit.

11. A steam generator having a plurality of steam generating tubes enclosing a space to form a combustion chamber, and means for supplying fuel to said chamber, said chamber having a dome composed of refractory material, said tubes being arranged in a plurality of groups each group consisting of two units and each group comprising a number of straight parallel tube lengths spaced apart approximately the thickness of the tube, and being connected by loops formed at their ends, the loops extending radially into said chamber, one unit being nested into the spaces between the tube lengths of the other unit, and one unit having larger loops extending into said chamber further than those of the other unit, said larger loops being shaped in configuration with said dome to shield the refractory material from the heat developed in the chamber.

12. A steam generator having a plurality of steam generating tubes enclosing a space to form a combustion chamber, and means for supplying fuel to said chamber, said chamber having a dome composed of refractory material, said tubes being arranged in a plurality of groups each group consisting of two units and each group comprising a number of straight parallel tube lengths spaced apart approximately the thickness of the tube, and being connected by loops formed at their ends, the loops extending radially into said chamber, one unit being nested into the spaces between the tube lengths of the other unit, and one unit having larger loops extending into said chamber further than those of the other unit, said larger loops being shaped in configuration with said dome to shield the refractory material from the heat developed in the chamber, and carriers fixed above said dome and adapted to engage the upper loops of both units to support each group of tubes in position.

13. A steam generator having a plurality of steam generating tubes enclosing a space to form a combustion chamber, and means for supplying fuel to said chamber, said tubes being arranged in a plurality of groups, each group consisting of two units and each unit comprising a number of straight parallel tube lengths spaced apart approximately the thickness of a tube, said lengths being con-

nected by loops formed at their ends, the loops extending radially into said chamber, one unit being nested into the spaces between the tube lengths of the other unit, and one unit having larger loops extending into said chamber further than those of the other unit, said chamber having a dome composed of bricks of refractory material and carriers fixed above said dome for supporting said bricks, some of said larger tube loops extending in front of said carriers to shield them from the heat developed in said chamber.

14. In a steam generator a combustion chamber having a dome and having a part of said dome and the chamber walls formed of steam generating tubes, the central portion of said dome comprising a removable element of refractory material and having means for introducing the fuel into said chamber.

20 In testimony whereof I affix my signature.
MARTIN EULE.
